France

Application December 10, 1948, Serial No. 150,063

Term of patent 7 years

(Cl. D58—6)

To all whom it may concern:

Be it known that I, Serge Heftler-Louiche, a citizen of France, residing at Paris, France, have invented a new, original, and ornamental Design for a Bottle, of which the following is a specification, reference being had to the accompanying drawing, forming part thereof.

In the drawing:

Fig. 1 is a front perspective view of a bottle showing my new design;

Fig. 2 is a rear elevational view thereof, and

Fig. 3 is a top plan view thereof. The sides of the bottle not shown have the same configuration and design as the front and rear thereof.

I claim:

The ornamental design for a bottle, substantially as shown and described.

SERGE HEFTLER LOUICHE.
